UNITED STATES PATENT OFFICE.

FRANK JOSEPH USHER, OF JAFFREY, BRITISH COLUMBIA, CANADA.

CYLINDRICAL CUTTER-HEAD FOR PLANING-MACHINES.

1,315,536.

Specification of Letters Patent.

Patented Sept. 9, 1919.

Application filed August 20, 1917. Serial No. 187,192.

To all whom it may concern:

Be it known that I, FRANK J. USHER, a citizen of the United States, residing at Jaffrey, British Columbia, in the Dominion of Canada, have invented a new and useful Improvement in Cylindrical Cutter-Heads for Planing-Machines, of which the following is a specification.

This invention relates to improvements in cutter heads for planing machines, and has for one of its objects to provide means for easily and positively fastening the cutter knives in said heads.

A further object of the invention is to provide means for loosening the knives so that they may be easily removed for sharpening.

A further object is to provide means for keeping the alinement of knives true throughout their length.

Still further objects and features of the invention will be more fully described in connection with the accompanying drawings, and will be more particularly pointed out in and by the appended claims.

In the drawing:

Figure 1 is a contracted plan view of the cutter head with two knives in place.

Fig. 2 is an end view of the cutter head with two knives in place.

Fig. 3 is a view of one knife in place on its holding plate.

Fig. 4 is a fragmentary sectional view through the cutter head showing one knife secured in position, and taken on line *c-c* of Fig. 1.

Fig. 5 is a sectional view taken on line *A-A* of Fig. 3.

Fig. 6 is a sectional view taken on line *B-B* of Fig. 3.

Fig. 7 is a perspective view of the extension block used when the cutting knife has worn down considerably.

Fig. 8 is a perspective view of the block used in adjusting the alinement of the knives.

Like numerals refer to the same parts throughout the various figures of the drawing.

50 Describing in detail the device of my invention 1 designates a cylindrical cutter head body and 2 the knives, which are fastened in the cylindrical body. 3 represents knife holding plates. 4 represents the wedge blocks used for tightening the knives and plates. 5 is the drawing set-screw used in

each of the blocks 4, having on its upper portion 6, threads in one direction, as for instance, right-hand, and on its lower portion 7, threads in the opposite direction (or 60 left-hand). At its center is a smooth portion 8.

Grooves 9 having knife and wedge block receiving portions 38 and 9' are provided in the cylindrical body 1. These grooves have 65 spaced threaded bores 10 in shoulders 11. The blocks 4 have threaded holes as indicated at 12, and have recesses 13 countersunk at the tops of said holes. When the recesses or counter-sunk portions 13, fill with pitch, 70 the wrench should be heated, to melt the pitch, whereupon, the wrench can readily be applied to the heads of the screws. It will be noted that the screws 5 are disposed with their axes inclined to the knife and 75 with the heads of the screws farthest from the knife and their bases nearest to the knife. Thus when the double threaded or differential screws 5, are turned in one direction, the wedge block 4, will be advanced toward 80 and against the plate 3, while if turned in an opposite direction, the wedge block will not only be drawn away from plate 3, but it will be retracted back into the block receiving portion so as entirely to free the 85 knife receiving portion for withdrawal or insertion of the knife. Further, because the screws 5 are threaded in the block, as well as in the cutter head, the wedge blocks will not only be positively loosened, but will 90 positively be held in a knife releasing position. The knives 2 are fastened to the plates 3 by means of countersunk screws 14. The plates 3 are supported in spaced relation from the bottom 15 of the grooves 9 by the 95 screws 16, more clearly shown in Fig. 3, to hold the knives in the desired degree of "set" projection. Each knife when mounted on its supporting plate has one or more alinement devices intermediate of its ends. 100 For the purpose of illustration I have shown one such device 17 at the center of the knife. A block 18 has beveled ends 19, and is slidably held between guide blocks 20. These guide blocks are fastened to plate 3 by 105 means of screws 21. An extension block 22 may be inserted between the block 18 and the knife 2. An adjusting screw 23 passes through a threaded hole 24 in the L portion 25 at the base of the plate 3. Said adjusting 110 screw has a smooth cylindrical end 26 which enters a socket 27 of block 18. Block 18 has

a V-shaped projection 28 which fits the V-recess 29 of extension block 22 when said extension block is in use. When said block is not in use, the V-shaped projection 28 fits the V-shaped recess 30 of knife 2. When extension block 22 is in use, its V-shaped projection 31 fits the recess 30 of knife 2. The plates 3 have at each end a series of staggered threaded holes 32. The knives 2 have at each end near the base a single countersunk, smooth, circular hole 33. Flat head screws 14 are adapted to be passed through holes 33 and into holes in the plate 32. When in such position the ends of the screws 14 will be flush with the surface of plate 3, and therefore will not interfere with the knife abutting uniformly against the side of the recess 9 when in place.

In assembling my cutter head, I take knife 2 and place its surface against the surface 37 of plate 3, bringing the holes 33, into registry with selected holes 32, so as to give me the desired general projection of the knife edge to compensate for wear of the knife. I then adjust the two outermost screws 16 to give the knife the fine "set" projection and to make this "set" projection uniform for all the knives. When the knife and the plate are thus secured and lined up, I adjust the balance of the screws 16 to just make contact along the base 15. I then place the wedge blocks in position and by turning set-screws 5, advance them securely against the plates 3 to hold the knives in the desired degree of "set" projection. When all of the knives have been thus secured in place, the cutter-head is ready for service.

It sometimes happens after sharpening knives that the center portion of the knife at the cutting edge is lower than the outer edges. In other words, that the cutting edge itself is convex. To remedy this trouble I make use of the alinement device 17, as above described. By tightening screw 23, the knife is stressed in its own plane and the cutting edge of the knife is straightened into perfect alinement. When the knife becomes thin through repeated sharpening, I insert the extension block 22, and in this way am able to use a shorter threaded space on the screw 23.

In removing knives from my cutter head I turn the set-screw 5 in the opposite direction from that which tightened the wedge block 4. This movement because of the double thread of my set-screw, forcibly lifts the wedge block 4 out of its recess, and because of the angle of the axis of the set-screw 5 with respect to the plane of the knife, the wedge block 4 is moved away from the knife, leaving the latter entirely free for its easy removal. This feature is a decided advantage over those now in use, and greatly facilitates the easy removal of knives for sharpening or replacements.

Now it will be clear that not only in making the general adjustment, to compensate for wear, by means of screws 14, and holes 32 and 33, but also in making the fine adjustment, by means of screws 16, all such adjustment can be made in the sharpening room and without stopping the planing machine. For instance, a separate set of knives can be maintained in the sharpening room, ready for insertion, and when they are inserted in the cutter head body, the knives will not only have the proper "set" projection of the cutting edge, but all the knives will have a uniform degree of projection from the cutter head, irrespective of wear of the knives.

It will also be noted that when the knife is being stressed to strengthen the cutting edge, the knife is rigidly held in a fixed position on plate 3, by screws 14, and after the knife has been stressed until its edge is straightened, it is held by that means which has been employed to stress the knife. In other words, the knife is not released after its edge is straightened.

While I have herein described one specific embodiment of my invention, I do not wish to be limited thereto, except for such limitations as the claims may impart.

I claim:

1. In a rotary cutter head structure for planing machines, a cutter head body provided with a groove having a knife receiving portion and a wedge block receiving portion and the latter having a face inclined from the radial and lengthwise parallel with the knife, a knife for insertion into the knife portion of said groove, a wedge block for the block receiving portion of said groove and having an inclined face for engagement with the inclined face of said groove, and a set screw having right and left hand thread sections, one section having threaded connection in said body and the other section having threaded connection in said wedge block, whereby rotative adjustment of said screw in one direction will actuate said wedge block to wedge lock the knife, and rotative adjustment in another direction will positively loosen and hold said block in a loosened position and free from obstructing projection with respect to the knife portion of said groove.

2. In a rotary cutter head structure for planing machines, a cutter head body provided with a groove having a knife receiving portion and a wedge block receiving portion, a knife for insertion into the knife portion of said groove with the butt edge of the knife radially innermost and the cutting edge radially outermost, a wedge block for the block portion of said groove, and a differential set screw having threaded connection with said body and block and extending alongside said knife but at an angle

thereto with the head of said screw farthest from said knife and the base nearest said knife.

3. In a rotary cutter head structure for wood planing machines, a cutter head body provided with a knife receiving groove, a knife and a knife holder in smooth abutting engagement with each other and adapted for insertion into said groove, said knife and holder having portions coöperating in combination with detachable means acting independently of said head body for rigidly fastening said knife and holder to each other in different positions with respect to each other prior to insertion thereof into said groove for securing said knife in an "in" or "out" position on said holder according to wear of the knife.

4. In a rotary cutter head structure for planing machines, a cutter head body provided with a knife receiving groove, a knife and a knife holding plate adapted for insertion into said groove, and adjusting devices on said plate for engagement with a portion of said groove for regulating the "set" of said knife, whereby said knife may be adjusted to a "set" position prior to insertion into said head, and means for rigidly fastening said knife to said plate.

5. In a rotary cutter head structure for planing machines, a cutter head body provided with a knife receiving groove, a knife and a knife holding plate adapted for insertion into said groove, means for fastening said knife in different positions on said plate according to the wear of said knife to obtain general uniformity of "set" of all the knives prior to insertion into said body, and adjustable devices on said plates for engagement with a portion of said grooves for obtaining a uniform set of all the knives irrespective of the extent of wear.

6. In a rotary cutter head structure for planing machines, a cutter head body provided with a knife receiving groove, a knife and a knife holding plate adapted for insertion into said groove, means for fastening said knife to said plate in any one of a plurality of positions according to the extent of sharpening wear of said knife, and adjusting devices on said plate adjustable prior to insertion into the head and coacting with a portion of said groove for supporting the knife at the proper "set."

7. In a rotary cutter head structure for planing machines, a cutter head body provided with a knife receiving groove, a knife and a knife holding plate adapted for insertion into said groove, means for fastening said knife to said plate in abutting relation side by side and in any one of a plurality of different positions according to the wear of said knife, said plate having an L-flange on its lower edge, and a plurality of adjusting screws in threaded engagement

with said flange and adapted for abutment against the bottom of said groove to support said knife in the required "set" position in said body.

8. As a means for alining the planing edge of an integral planing knife, a knife holding plate, a knife for said plate, means for fastening the ends of said knife to said plate to obtain the required projection of said knife edge, and means on said plate for engaging a central portion of said knife to stress the knife in its own plane until the cutting or planing edge is straightened.

9. In a rotary cutter head structure for planing machines, a cutter head body provided with a knife receiving groove, a knife and a knife holding plate adapted to be inserted in said groove, means for fastening the ends of the knife to the plate prior to insertion, means on said plate for engagement with a central portion of the knife to stress the knife in its own plane and straighten the cutting edge prior to insertion and holding the knife to a straight edge after insertion, and means for coaction with said plate and a portion of said groove for supporting the knife at the proper "set".

10. In a rotary cutter head structure for planing machines, a cutter head body having a groove provided with a knife and a wedge block portion, and a set screw having right and left hand threaded sections, one section engaging said body and the other section engaging said block, and said screw being set at such an angle that when loosening adjustment is applied thereto the screw will loosen the wedge block and draw it away from the knife portion of said groove.

11. In a rotary cutter head structure for planing machines, a cutter head body provided with a groove having a knife receiving portion and a wedge block receiving portion and the latter having a block engaging face inclined from the radial, a knife for insertion into said knife receiving portion, a one piece wedge block for the block receiving portion of said groove having an inclined face for engagement with the inclined face of said block receiving portion for bodily movement of the block parallel with and toward the knife to be held, and a set screw having right and left hand threaded sections, one section having threaded connection with said body and the other section having threaded connection with said block, and said screw being inclined to the knife with its head farthest and its base nearest the knife, whereby rotative adjustment of said screw in one direction will bodily actuate said block to wedge-lock said knife and rotative adjustment of said screw in another direction will positively loosen and move said block away from said knife receiving portion and free the latter from obstructing projection by said block.

12. In a rotary cutter head structure for wood planing machines, a cutter head body provided with a knife receiving groove, a knife and a knife holder adapted for insertion into said groove, said holder and knife having openings at their ends, and pins adapted for insertion through said openings for rigidly fastening said knife and holder together with the knife in different positions

of "in" or "out" "set" prior to insertion of 10 the holder and knife into said groove.

In testimony whereof, I hereby affix my signature in the presence of two witnesses.

FRANK JOSEPH USHER.
